UNITED STATES PATENT OFFICE.

THURE E. DAHL, OF NEW YORK, N. Y.

DESIGN FOR A RING FOR LIGHTING FIXTURES.

Application filed July 21, 1921. Serial No. 486,579. Term of patent 3½ years.

To all whom it may concern:

Be it known that I, THURE E. DAHL, a subject of the King of Sweden, and resident of New York, in the county of New York and State of New York, have invented a certain new, original, and ornamental Design for a Ring for Lighting Fixtures, of which the following is a specification, reference being had to the accompanying drawings, forming part thereof.

Fig. 1 is a side elevation of a ring for

lighting fixtures, showing my new design. Fig. 2 is an outline view of the same, a part of the surface ornamentation being shown.

Fig. 3 is a fragmentary view, showing the surface ornamentation of the same.

I claim:

The ornamental design for a ring for lighting fixtures, as shown.

THURE E. DAHL.
